UNITED STATES PATENT OFFICE.

WILLIAM A. NORDSTROM, OF JAMESTOWN, NEW YORK.

ACCELERATOR FOR MOTOR-CAR ENGINES.

Application filed October 28, 1921. Serial No. 511,203.

To all whom it may concern:

Be it known that I, WILLIAM A. NORDSTROM, a citizen of the United States, residing at the city of Jamestown, in the county 5 of Chautauqua and State of New York, have invented certain new and useful Improvements in Accelerators for Motor-Car Engines, of which the following, taken in connection with the accompanying drawings, is a specification.

The invention relates to pedal accelerators and is especially adapted to internal combustion engines in motor cars; and the object of the improvement is to provide a sidewise 15 extending pedal having a radially toothed adjustable coupling to an actuating lever for the carburetor to adjust said pedal to the foot boards of motor cars, said sidewise extension of the pedal permitting direct 20 attachment to said carburetor through the dash board by means of said actuating lever, a resilient link, and a throttle plate, adjustable rod connection being provided between said throttle plate connection and the steering 25 post on the opposite side of the engine for manual acceleration, thereby giving a direct positive connection to the carburetor on the right side of the same and simplifying and strengthening the entire structure, 30 rendering it more adaptable to different motor car constructions; and the invention consists in the novel features and combinations hereinafter set forth and claimed.

In the drawings, Figure 1 is an elevation 35 of the right side of the engine showing the accelerator mechanism attached to the dash board of the motor car. Fig. 2 is a top plan view of the accelerator mechanism as attached to the dash board and connected to the carburetor and the throttle rod of the steering post. Fig. 3 is a perspective view 40 of the sidewise extending pedal with its radially toothed flange for adjustable coupling with the upper end of the operating lever. Fig. 4 is a top plan view of said upper end of the operating lever showing the second half of the radial flange coupling and the plate which pivotally supports the operating lever on the dash board. Fig. 5 45 is an elevation of said operating lever with the attaching plate pivotally attached thereto. Fig. 6 is an elevation of the resilient link joint between the throttle plate and the lower end of the operating lever. Fig. 7 is 50 a perspective view of the throttle plate and bracket piece with a portion of the connect-

ing rod to the throttle rod of the steering post as connected to the carburetor. Figure 8 is a detailed perspective of the lever spring.

Like characters of reference refer to corresponding parts in the several views.

The numeral 10 designates the sidewise extending pedal which has the foot plate 11 at one end and the flange 12 with the radial teeth 13 near the other end, said other end being threaded at 14 to permit attachment to the operating lever 15 by means of a suitable screw nut 16, and the flange coupling 12 17.

The upper end of the lever 15 has the flanged enlargement 17 which is radially toothed at 18 to adjustably enter the teeth 13 of the flange 12, thereby adjustably attaching the pedal end 11 at the desired 70 height above the foot board 19 in the different motor cars. A plate 20 is pivotally attached at 21 to the upper portion of the lever 15 for attachment to the dash board 22 by means of suitable screw bolts 23, 75 which operating lever extends through said dash board and plate. The actuating lever 15 has the downwardly turned end 24 which extends downward nearly to the level of the top of the carburetor connection 25.

A strong spring 26 is attached by its looped upper ends 27 and the screw bolts 23 to the dash board 22, thereby normally drawing the lever 15 strongly toward the dash board 22 and returning the actuating 90 lever 15 and pedal 10 to the normally raised position ready for renewed actuation. The lower end of the actuating lever 15 has the eye 28 to receive therein the hooked end of the link 29 which connects said lower end 95 24 to the throttle plate 30.

The link 29 is made resiliently adjustable by being made in two parts 31 and 32 which loop around one another and retain therebetween the coil spring 33 so as to normally hold said parts 31 and 32 apart. This is rendered necessary by the manual actuation from the rod 40 on the steering post since if the link 29 would not resiliently permit the manual actuation of the operating arm 100 36 of the carburetor 25, then such manual actuation would have to operate the pedal actuating parts or be held thereby from manual actuation. Accordingly in order to permit the free and easy manual actuation 105 through rod 40, this resilient construction of the link 29 is arranged. A stop-washer 35

is attached on the part 32 of the link 29 so that when pedal actuated, the part 31 will press against said stop 35 as shown in Figs. 1 and 2, and when manually actuated, the 5 stop 35 and part 32 will be drawn away from the part 31 as shown in Fig. 6. The spring 33 will throw all the parts back to the normal pedal or manual actuating position with the loop on the part 31 pressing against the 10 stop 35.

The link part 32 is preferably attached to the throttle plate 30 by means of a pin 34 with enlarged head to receive the end of the 15 part 32 of the resilient link 29 in threaded engagement through said head.

A cotter pin 46 is inserted through a hole in the end of the part 32 which engages on a portion of the head 34, thereby preventing the turning of the part 32, holding it in 20 alignment with the part 31 of the resilient link 29. Said part 31 is held in line by the insertion of its hooked end in the hole 28 in the end of the lever 15.

The pin 34 is attached in the end of the 25 throttle plate 30 preferably by a removable cotter pin. It would not depart from my invention, however, to turn the end of the throttle plate 30 upward to receive the end of the link 32 therethrough, or to turn the 30 end of said link downward through the hole in the throttle plate 30. The present construction is preferred merely because of the possibility of closer adjustment therewith.

The throttle plate 30 is provided with a 35 bifurcated portion forming downwardly extending lugs 30' which are desired to freely straddle the operating arm 36 of the throttle valve of carburetor 25 by means of a suitable screw bolt 37, which screw bolt also attaches 40 the angle bracket 38 which supports the end of the connecting rod 39 to the manual throttling rod 40. The connection to the steering post 40 is attained by means of the bracket 41 and adjusting plate 42 and screw 45 thread 43 with cotter pin 44 in the end of the rod 39 to prevent its turning or withdrawal in case the threads should strip in the ends of said rod. The rod 39 extends 50 across through the engine 45 drawing directly upon the rod 40 of the steering post when the carburetor is operated manually.

In accelerating the speed of the engine by 55 depressing the pedal 11 the link element 31 is caused to slide on the link element 32 until the former is engaged with stop 35 whereupon the link elements constitute a positive connection between the lever 15 and the throttle plate 30. During this operation the rod 39 slides through the plate 42. 60 Upon releasing the pedal from pressure the spring 26 returns the several parts to normal position. When the engine is under manual control so that a pull on rod 39 is required to open the throttle, the link element 32 will 65 then slide on the link element 31 and com-

press the spring 33 so that when the manual control is released said spring will tend to restore the several parts to their normal position.

It is now apparent that my simple accelerating mechanism may be quickly and easily installed upon motor cars, the assemblage being exceedingly simple and adjustment accurate and exact, the sidewise extending 70 pedal 10 being of sufficient length to be 75 easily operated along with the other operating levers without sidewise foot movement.

What is claimed as new is:

1. In combination with an operating arm of a throttle valve, an actuating lever, an elongated throttle plate having one end secured to the free outer end of the arm and formed with a pair of lateral, depending ears for freely straddling said outer end of the arm to prevent relative pivotal movement between said arm and plate, and means connecting the opposite end of the plate to the lever.

2. In combination with a motor car, an engine accelerator comprising a bracket plate attached to the dash board of said car, an angular operating lever pivotally attached through said plate, a sidewise extending foot pedal adjustably attached to the upper end of said operating lever, resilient link connection between the lower end of said actuating lever and the throttle plate of the carburetor, and a bowed spring secured at its ends to said dash board and having its intermediate portion extending over said actuating lever to normally hold said sidewise extending pedal in the normally raised position for foot actuation.

3. In combination with a motor car, an engine accelerator comprising a bracket plate attached to the dash board of said car, an angular spring operating lever pivotally attached to said plate, a sidewise extending foot pedal, a radially toothed flange coupling between said sidewise extending pedal and the upper end of said angular operating lever to adjust the position of said pedal as to the foot board of the motor car, a spring controlled link connecting the lower end of said operating lever and the throttle plate for the carburetor, said throttle plate having downwardly extending lugs each side of the actuating lever for the carburetor, and adjustable rod connection between said carburetor arm and the steering post of the 120 motor car to permit hand actuation of said carburetor.

4. An engine accelerator comprising an angular spring operating lever and means for pivotally attaching said lever to the dash board of a motor car, a sidewise extending foot pedal from said operating lever and means for adjusting the relation of said foot pedal to the foot board of the motor car, a throttle plate for the carburetor, a resilient 130

link connecting the end of said operating lever to said throttle plate, said throttle plate engaging the actuating lever of the carbureter to actuate the same, said resilient link comprising two parts looped around one another to form a slidable engagement on one another, a coil spring on one of said parts between the loop portions to resiliently hold said loop portions a distance apart, a stop 10 on the link portion attached to said throttle plate to receive the looped end on the other part and permit pedal actuation by means of said resilient link, and an adjustable rod connection between the actuating arm of said 15 carbureter and the throttle rod of the steering post to permit manual and pedal actuation of said carbureter without interference.

5. In combination with an operating arm of a throttle, an actuating lever, and a resilient connection between the arm and lever and comprising a pair of link elements having overlapping portions formed with terminal eyes slidably receiving the companion link element, a spring interposed between 20 the terminal eyes tending to extend the link 25

elements relatively to each other, and a stop on one element beyond the spring to be engaged by the opposite terminal eye to establish a positive push connection between the lever and arm. 30

6. In combination with a motor car, an engine accelerator comprising a bracket plate attached to the dash board of said car, an angular operating lever pivotally attached through said plate, a foot pedal attached to the upper end of said operating lever, a connection between the lower end of said actuating lever and the throttle plate of the carbureter, and a bowed spring secured at its ends to said dash board and having its intermediate portion extending over said actuating lever to normally hold said pedal in the normally raised position for foot actuation. 35

In testimony whereof I have affixed my signature in the presence of two witnesses. 40 45
